United States Patent Office.

BERNARD HAVANAGH, OF NEW YORK, N. Y.

Letters Patent No. 79,117, dated June 23, 1868; antedated June 13, 1868.

IMPROVEMENT IN WASH-BASIN OVERFLOW AND DISCHARGE-PIPES.

The Schedule referred to in these Letters Patent and making part of the same.

TO ALL WHOM IT MAY CONCERN:

Be it known that I, BERNARD HAVANAGH, of the city and State of New York, have invented, made, and applied to use, a certain new and useful Improvement in Setting Wash-Basins; and I do hereby declare the following to be a full, clear, and exact description of the said invention, reference being had to the annexed drawing, making part of this specification, wherein—

Figure 1 is a vertical section of said basin and its attachments, and

Figure 2 is a sectional plan at the line $x x$.

Similar marks of reference denote the same parts.

My invention is intended to remove the risk of injury to buildings resulting from leakage of the couplings and connections of basins, and at the same time facilitate repair.

I make use of a metallic drip-pan beneath the basin, in which is formed a trap for the waste-pipe, and I support the basin upon a hollow screw that forms the vertical waste-pipe, so that risk of leakage is prevented, and the fitting up of the plumbing-work is greatly facilitated.

In the drawing, a represents a slab of marble or other material; b and c are the basin-cocks for hot and cold water of any usual character.

d is my metallic drip-pan, which I prefer to have made of cast iron. The pipes that supply water to the cocks b and c pass up through thimbles or raised projections in the said pan d , and are packed with putty or suitable cement, so that any leakage, consequent upon the coupling of either cock becoming loose, the water is received by this pan d .

This pan d is set upon the floor or any suitable support, and is formed with a box, e , that is on the under side of said pan, and communicates to the sewer-pipe f , and acts as a trap to exclude smell, the cylindrical projection 2 reaching to the surface of the water that remains in the box e .

The cylinder 3 rises above the pan d , and is provided with an interior thread that receives the screw of the tubular column g , at the upper end of which is a ring-seat, 4 , for the basin 5 , and l is a hollow arm from the column g to the overflow-horn 6 of the basin 5 .

It will now be understood that when the column g is screwed down into the box e , the basin can be placed on the ring-seat 4 , with suitable packing at the junction of the parts, the horn 6 entering the arm l , and the two are rotated until the upper edge of the basin is firmly pressed against the under side of the slab, putty or other suitable cement being employed at this point to make a tight joint.

This construction allows for the introduction or removal of basins with facility, and any leakage cannot fail to be taken by the drip-pan d , and from that be conveyed to the sewer by a pipe, m . This pipe m should be connected to the main sewer-pipe to avoid the risk of an overflow if the pipe f should become stopped at some distance from the drip-pan d , but, if desired, this pipe m might connect directly to the pipe f , as shown by dotted lines, fig. 2.

What I claim, and desire to secure by Letters Patent, is—

The trap e and pipe f below the drip-pan d , in combination with the hollow column g , supporting the basin, and arranged to receive its discharge and overflow, as and for the purposes set forth.

Dated October 14, A. D. 1867.

BERNARD HAVANAGH.
